SUPPORT RAIL FOR ROLLERS OF A GRAVITY CONVEYOR

Charles P. Tabler, Hamilton, Ohio, assignor to
Kornylak Corporation, Hamilton, Ohio

Filed Mar. 10, 1975, Ser. No. 556,950

Term of patent 14 years

Int. Cl. D12—05

U.S. Cl. D55—1 C

FIG. 1

FIG. 2

FIG. 3

FIG. 4

FIG. 5

FIG. 6

FIG. 7

FIG. 1 is a perspective view of my new design for a support rail for rollers of a gravity conveyor showing the rail of indefinite length in a position wherein conveyor rollers would be secured thereon for supporting articles to be conveyed;

FIG. 2 is a front view thereof;

FIG. 3 is a right side view thereof;

FIG. 4 is a rear view thereof;

FIG. 5 is a top view thereof;

FIG. 6 is a left side view thereof; and

FIG. 7 is a bottom view thereof.

I claim:

The ornamental design for a support rail for rollers of a gravity conveyor, as shown and described.
